CARTON OF VITAMIN PACKAGES

Seymour Robins, New York, N. Y.

Application December 3, 1952, Serial No. 22,537

Term of patent 14 years

(Cl. D58—12.6)

To all whom it may concern:

Be it known that I, Seymour Robins, a citizen of the United States, residing at New York, in the county of New York and State of New York, have invented a new, original, and ornamental Design for a Carton of Vitamin Packages, of which the following is a specification, reference being had to the accompanying drawing, forming part thereof, in which:

Figure 1 is a perspective view of a carton of vitamin packages showing my new design;

Figure 2 is a side elevational view of the carton;

Figure 3 is an end elevational view of the carton; and

Figure 4 is a top plan view of the carton.

The sides of the carton not shown are the same as the sides shown.

I claim:

The ornamental design for a carton of vitamin packages, as shown and described.
